FOOT SWITCH

Irvin Earl Nixon, Houston, Tex., assignor to M. O. Scobee and himself, both of Houston, Tex.

Application July 30, 1936, Serial No. 93,501

2 Claims. (Cl. 200—159)

My invention relates to switches especially the type operated by the foot, said switches being used in connection with telephone, telegraph, signal systems or the like for various switching purposes.

The object of this invention is to provide a foot switch that will operate efficiently with a minimum of effort on the part of the user; also to lift up the circuit controlling or switching means a suitable distance above the flooring in the vicinity of the foot pedal of said switch, thereby clearing said switching means from exposure to dust, dirt and moisture which invariably collects upon the flooring or other surfaces where such apparatus is located.

The novel features of the invention will be apparent from the following description taken in connection with the accompanying drawings in which—

20 Fig. 1 is a partial sideway elevation of a foot switch, the circuit switching means enclosed in switch box 1.

Fig. 2 is a side elevation of the switch shown in Fig. 1 on a line 2—2 of Fig. 1.

25 Fig. 3 is a partial detail view of the switching lever arrangement on a line 3—3 of Fig. 2. The aforementioned detail illustrates the operation of the lever 2 in connection with the push button switch 3.

30 Fig. 4 is a detail view of the switch box 1 showing the internal wiring of the same; also showing external connections with the telephone mouth piece 5; and also with the battery B. The position of the push button switch 3 as shown in Fig. 4 disconnects the battery B from the wired circuit.

35 Fig. 5 is a further detail of the switch box showing the manner of the operation of the push button switch 3 in connection with the multiple jack 4. The position of the switch 3 cuts the battery B into the circuit.

40 Fig. 6 is a modification of a foot switch mechanism, the connecting rod operating in a ball socket 6.

45 Fig. 7 is a further modification of a foot switch mechanism involving the operation of the connecting rod operable by the kicking of or by a sidewise rotatable movement of the foot pedal.

50 Fig. 8 is a further modification of a foot switch mechanism involving the operation of the connecting rod by means of the transverse bar 9.

55 Referring to the drawings, the foot switch proper is mounted upon an upright frame 12. The numeral 1 designates the switch box or container in which the circuit wiring and switch jack is contained. Said switch box is mounted

on said frame 12 which is made of wood or the like. The upright frame 12 is slotted at the location designated as 12^a and the floor pedal 9 is fitted into said slot. Said pedal is pivotally mounted on the bearing 9^a.

The retractile spring 11 restores the pedal 9 to normal position when said pedal is released by the user's foot. Mounted upon said pedal is the connecting rod 7 which is connected to the arm 2^a of the bell crank 10; said bell crank is 10 movable on the bearing 10^a. The bell crank 10 is secured to the upright frame 12 by means of the screws 2^b. The lever arm 2 of the bell crank 10 rests upon or is closely contiguous to the push button 3 the pin of which projects through 15 a bushing in said switch box as shown.

When the foot pedal 9 is pressed by the foot the connecting rod 7 moves the arm 2^a and with it the bell crank 10 causing the lever arm 2 to push the button 3 inward. The above action 20 causes the push button 3 to be forced inward by the lever arm 2.

The circuit arrangement in connection with the foot switch shown in Fig. 4 is a typical cut out key arrangement for telephones generally 25 used in train dispatching. The cut out key normally keeps the battery disconnected from the circuit. When it is desired to talk into the telephone transmitter 5, the user will press the foot pedal 9 which will cause the nose 3^a of the push button 3 to press against the joined contact springs or fingers 13 and 13^a causing said fingers to move to the left and contacting with the springs 14, 15 and 16. The contacting of the springs of the multiple jack 4 as just described 35 is shown in Fig. 5.

In Fig. 4 the push button 3 is released from the contact spring or finger 13 resulting in the disconnection of the battery B from the telephone circuit.

40 An insulated rod 13^b joins the contact springs 13^c and 13^a together so that they may contact with the respective contact spring simultaneously.

The circuit connections in the switch box 1 are of the usual type that are incorporated in many 45 telephone systems and are well known to the art and do not require detailed description.

Connected in the aforesaid circuit is the condenser 15, the function of which is well known to the art.

50 Referring to Fig. 6. The connecting rod 7 rests in a ball bearing base 6. Mounted on the connecting rod and secured thereto is the foot pedal 9. The connecting rod 7 is secured at its upper end to bearing 16 which is secured in turn to the 55

switch box 1 by means of a pair of screws. The rod 7 is provided with an extension lever 17 which contacts with the push button 3. When the pedal 9 is pushed in the direction of the arrow shown 5 in the figure, the lever 17 is caused to contact with and move the push button switch 3 inward into the switch box 1 causing the contacting of the multiple jack 4 in the manner as described with reference to the operation of the foot switch 10 shown in Fig. 1.

The connecting rod 7 is retracted by the spring 11^a in the usual manner.

Referring to Fig. 7, the foot pedal 9 is connected to the connecting rod 7 which is pivoted 15 at the arbor 18 and said rod swings thereon. Mounted upon the switch box 1 is the bell crank 10^b. The upper end extension 7^a of the rod 7 rests outwardly upon the lever 10^c of the bell crank 10^b. When the user's foot strikes the 20 pedal 9 and thus moving it in the direction of the arrow shown in the figure, the upper end extension 7^a of the rod 7 will move the lever 10^c of the bell crank 10^b. This movement will cause the lever 10^d to move the push button switch 3 25 performing the function as already described. The retractile spring 11^b will restore the foot pedal 9 to normal when released by the user's foot.

Referring to Fig. 8, the lift rod 7 is secured 30 at its lower end to transverse rod 19 by means of the jointing member 19^a, said transverse rod is secured to a U-shaped pedal rail 8, said pedal rail or bar being pivoted in bearings 8^a. The upper extension of the connecting rod 7 is secured to the lever 10^e of the bell crank 10^f. The lever 10^g of said bell crank contacts with the push button switch 3.

When the pedal rail or bar is depressed by the user's foot in the direction shown by the arrow 40 in Fig. 8, the lever 10^e will move downward which will cause the lever 10^g to press against the push button switch 3 resulting in contacting of the

multiple jack 4 in the manner already described. The retractile spring 11^c will restore the pedal rail 8 to its normal position when released by the user's foot.

Referring to Fig. 4 the push button switch 3 5 is retracted to the position shown in said figure when released by the lever arm 2 of the bell crank 10.

It is obvious that the foot switch arrangement as shown has uses other than that particularly 10 described and I therefore do not wish to confine myself to said particular usage.

Now having described my invention, what I claim is—

1. In a device of the class described including 15 a switch, said switch having a series of vertically disposed contact members, a housing for completely enclosing said switch, a bushing in said housing, a plunger rod movable through said bushing, said plunger rod causing the contacting 20 of said vertically disposed contacting members, a bell crank lever having an arm in operable contact with said plunger rod, a connecting rod operably connected to said bell crank, and a foot pedal operably connected to said connecting rod, 25 said switch and housing therefor elevated above the connecting rod aforesaid.

2. In a foot switch of the class described including a foot pedal, an upright rod connected thereto, a bell crank having an arm connected 30 to said rod, a switch comprising a series of contact springs, a housing enclosing said switch, a plunger member projecting inwardly into said housing and being moved in a horizontal plane by said bell crank, said projected movement of said 35 plunger member causing the contacting of said contact springs in one direction, and the retracting movement of said plunger member causing the contacting of said contact springs in an opposite direction, said housing being elevated 40 above the bar member and foot pedal aforesaid.

IRVIN EARL NIXON.
